CLAIM

The ornamental design for a network attached storage device, as shown and described.

DESCRIPTION

FIG. 1 is a front, left, top perspective view of a network attached storage device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right, bottom perspective view thereof.

The broken lines shown represent portions of the network attached storage device that form no part of the claimed design.

1 Claim, 7 Drawing Sheets(56)
